United States Patent Office

Des. 212,975
Patented Dec. 17, 1968

212,975

PHOTOGRAPHIC COPYING APPARATUS

Kenneth W. Scott, Rochester, N.Y., assignor to Eastman
Kodak Company, Rochester, N.Y., a corporation of
New Jersey

Filed Sept. 15, 1967, Ser. No. 8,604

Term of patent 14 years

(Cl. D61—1)

FIG. 1

FIG. 4

FIG. 2

FIG. 3

FIGURE 1 is a left side, top and front perspective view of a photographic copying apparatus showing my new design;

FIGURE 2 is a right side elevational view, to a reduced scale, the left side being substantially a mirror image thereof;

FIGURE 3 is a rear elevational view thereof; and

FIGURE 4 is a bottom plan view thereof.

I claim:

The ornamental design for a photographic copying apparatus, as shown and described.
